ANIMAL TOY

Howard William Beaver, Eagle Rock, Calif.

Application November 12, 1943, Serial No. 509,967

6 Claims. (Cl. 46—104)

This invention relates to toys and deals particularly with an animal toy that is adapted to be pulled along the floor.

The hereinafter described toy has been made to simulate a dog. But it is to be understood that the novel feature embodied in this invention may be incorporated without modification on other toy animals besides the one illustrated, the only requirement being that the animal have a tail.

An object of the invention is to provide a tail wagging mechanism on toys of the character described which will be operated upon pulling the toy along the floor. Another object is to provide a toy animal mounted upon wheels wherein the rotation of a pair of wheels is utilized to wag the tail of the animal. A more specific object is to provide a toy of the character described wherein the tail wagging means comprises a pair of complementary opposed cam faces adapted to be rotated with the wheels of the toy to oscillate a pivotal member on the body of the toy which simulates the wagging tail of an animal. A further object is to provide a toy constructed of wood wherein the body and the wheels of the toy are cut from plain board lumber. Other objects and advantages will become apparent as the description proceeds in conjunction with the drawing in which:

Figure 1 is a view taken on line 1—1 of Figure 2;

Figure 2 is a top plan view of Figure 1;

Figure 3 is a view taken on line 3—3 of Figure 4;

Figure 4 is a pair of wheels showing the cam arrangement; and

Figure 5 is a view of the cam element which is attached to the wheels.

Referring to the drawing it will be seen that my invention is embodied in a toy exemplified in this instance as a dog. As shown, the dog's body is divided into two portions 11 and 12 which are cut from board lumber. The sections are hinged together in the central portion on a pivot 13. A pair of wheels 14 mounted on a shaft 15 is used to support the section 11 by passing the shaft 15 through a hole 16 in the section. The shaft 15 is held against longitudinal movement by pin members 17. The section 11 may also be provided with material 18, such as black oilcloth or the like, which may be cut to represent ears and suitably attached to the section by means of small tacks 19 or the like. The head of the dog may be provided with eyes 20, which may be thumb tacks or any equivalent member

that may be mounted in the wood of the section, or the eyes may be glued on if desired. A string 21 may be attached in any suitable manner for pulling the toy.

5 The rear section 12 is likewise carried on wheels 22 and 23 attached to a shaft 24, the section 12 being provided with a hole 25 for rotatably receiving the shaft. Mounted upon the wheels 22 and 23 are cams 26 and 27 respectively. It is to be understood that the wheels 22 and 23 are fixed on the shaft 24 and that the cams 26 and 27 are fixed on the wheels 22 and 23 so that the high points of the cams are substantially 180° of rotation apart.

10 The preferred type of cam used is best illustrated in Figures 3, 4, and 5. Here it will be observed that the cam member 26 mounted on the wheel 22 is a V-shaped member best seen in Figure 5. This member may be cut from wood or 15 any other suitable material and may be attached to the wheel either by gluing or nailing. In Figure 4 it will be noted that while the cam member 26 is above the shaft, the cam member 27 is below the shaft, thus spacing the cams substantially 180° of rotation apart. The cam members 26 and 27 will be noted in Figure 2 to come 20 substantially flush with the sides of the member 12. This provides against endwise movement of the shaft 24 in the member 12.

25 Referring to Figure 1, it will be seen that the rear end of the section 12 is provided with a slot 28. Extending into the slot 28 is a member 29 which is for the purpose of simulating the tail of a dog. This member may be of plain board lumber or it may be of any suitable substance, such as plastic, etc. The tail 29 is pivotally mounted in the slot 28 by means of a nail 30, or its equivalent, which may be driven through the section 12 and the member 29 at any suitable point, the only requirement being that a sufficient length of the tail extend beyond the pivot into the slot 28 to provide a leverage for 30 rocking the member 29 on its pivot 30.

35 At the lower part of the tail 29, I provide a pin which extends outwardly on both sides of the member itself, thus forming upstanding pins 30' and 31 on opposite sides of the member which are adapted to be engaged by the cams 26 and 27 respectively upon rotation of the wheels 22 and 23. As before stated, these cams are spaced substantially 180° apart and, as their sloping faces alternately hit the pins 30' and 31, the member 29 is forced to oscillate upon the pivot point 30. The result is that the member 29 is 40 moved from the full line to the dotted line posi- 45

tion in Figure 2, which gives a simulation of a wagging tail.

A noteworthy feature of the construction is the fact that practically all parts of the toy are made from board lumber with few cuts. For instance, the wheels are cut from the same board lumber as the body members 11 and 12 and the pivot points are made by driving a nail through both members at a suitable point. A toy of the above character lends itself remarkably well to low cost of manufacturing and provides an inexpensive, durable toy for the purpose set forth.

As the toy is pulled along the floor the wheels 22 and 23 are forced to rotate. The pins 30 and 31 will slidably engage the inside surface of the wheels and will trace a path shown by dotted line P. Since the cams 26 and 27 are attached to the wheels they will alternately engage the pins 30 and 31 and force the tail 29 to rock on its pivot, thus giving a simulation of a tail wagging dog.

I claim:

1. In an animal toy having a body portion, a tail wagging mechanism consisting of a pair of wheels spacedly fixed on a shaft, means for rotatably mounting said shaft in said body portion with the body portion substantially intermediate said wheels, said wheels each having an inwardly facing cam thereon extending substantially to said body, a tail pivotally mounted on said body portion, and means on said tail for engaging said cams to oscillate said tail on its pivot when said wheels are rotated.

2. In an animal toy having a body portion mounted on wheels wherein a pair of wheels is fixed to a shaft that rotates in the body portion, a tail wagging mechanism consisting of a tail member pivotally mounted on said body, an inwardly facing cam on each wheel of said pair of wheels adapted to slidably engage said body portion on opposite sides thereof, and means on said tail for engaging said cams, said cams being spaced with respect to rotation to alternately engage said means to cause a rocking motion of said tail when said wheels are rotated.

3. In an animal toy having a body portion mounted on wheels wherein a pair of wheels is fixed against rotation with respect to each other, a tail wagging mechanism consisting of a tail

member pivotally mounted on said body, an inwardly facing cam on each wheel of said pair of wheels adapted to slidably engage said body portion on opposite sides thereof, and means on said tail for engaging said cams, said cams being spaced with respect to rotation to alternately engage said means to cause a rocking motion of said tail when said wheels are rotated.

4. In an animal toy having a body portion mounted on wheels wherein a pair of wheels is fixed to a shaft that rotates in the body portion, a tail wagging mechanism consisting of a tail member pivotally mounted on said body, inwardly facing V-shaped blocks mounted on said wheels adapted to slidably engage said body portion on opposite sides thereof, and means on said tail for engaging said blocks, said blocks being spaced with respect to rotation to alternately engage said means to cause a rocking motion of said tail when said wheels are rotated.

5. In an animal toy having a body portion mounted on wheels wherein a pair of wheels is fixed to a shaft that rotates in the body portion, a tail wagging mechanism consisting of a tail member pivotally mounted on said body, a V-shaped block mounted on the inner face of each of said wheels, the apex of each of said V-shaped blocks being adapted to slidably engage the said body portion on opposite sides thereof to form a stop against longitudinal movement of said shaft in the body portion, and means on said tail for engaging said blocks, said blocks being spaced with respect to rotation to alternately engage said means to cause a rocking motion of said tail when said wheels are rotated.

6. In an animal toy having a body portion mounted on wheels wherein a pair of wheels is fixed against rotation with respect to each other and said body portion has a slot therein, a tail extending into said slot and pivoted near the upper end of the slot, laterally extending members on the lower end of said tail, and an inwardly facing cam on each of said wheels arranged to slidably engage said body portion on opposite sides thereof and to alternately engage said extensions and rock said tail on its pivot upon rotation of said wheels.

HOWARD WILLIAM BEAVER.
